CLAIM

The ornamental design for a border portion and grooves in front surface of a basketball backboard, as shown and described.

DESCRIPTION

FIG. 1 is a front elevation view of the border portion and grooves in front surface of a basketball backboard showing our new design;

FIG. 2 is a cross section view taken along line 2—2 in FIG. 1;

FIG. 3 is a front elevation view of a second alternate embodiment; and,

FIG. 4 is a cross section view taken along line 4—4 in FIG. 3.

The broken line showing of the backboard, goal, and net is for illustrative purposes only and forms no part of the claimed design.
